UNITED STATES PATENT OFFICE.

CHARLES W. WYMAN, OF CLAREMONT, NEW HAMPSHIRE, ASSIGNOR TO SULLIVAN MACHINERY COMPANY, A CORPORATION OF MASSACHUSETTS.

MINING MACHINE.

Application filed July 14, 1923. Serial No. 651,848.

My invention relates to mining machines and more particularly to protective devices for the electrical controlling apparatus thereof.

5 An object of my invention is to provide an improved protective device for controller cover plates used on electric mining apparatus whereby the unauthorized removal of the same is prevented. A still more specific object of my invention is to provide an improved protective device for preventing the removal of cover plates used on electric mining machines of the explosion proof type adapted for use in gaseous mines, whereby 15 the unauthorized removal of the same at the mine face or in a gaseous atmosphere is prevented and the consequent possibility of an explosion caused by the arcing or sparking of the electrical contacts igniting the mine 20 gas is eliminated. These and other objects and advantages will, however, hereinafter more fully appear.

In the accompanying drawings I have shown for purposes of illustration one embodiment which my invention may assume in practice.

In these drawings:

Fig. 1 is a side elevation of the rear end of a mining machine embodying my improved device.

Fig. 2 is a detail horizontal sectional view taken substantially on line 2—2 of Fig. 1.

Fig. 3 is a detail sectional view taken on line 3—3 of Fig. 2.

35 In this illustrative construction I have shown a mining machine of the flexible fed type including a casing or frame 1 slidable on its bottom 2 on the mine bottom and adapted to be fed relative to the mine face 10 to cut a kerf or slot therein by means of flexible feeding means not shown. The cutting and feeding mechanism may be of any approved type adapted to be driven by a suitable motor disposed in a casing 3, herein 45 an electric motor, controlled by any suitable electrical controlling mechanism, not shown, operated by a handle 4 suitably carried by the machine frame.

Formed in the machine frame is a chamber 5 in which the controlling apparatus is disposed. This chamber 5 is herein provided with a closure member or plate 6 tightly held in position by means of bolts 7. To prevent the possibility of an unauthorized removal of the plate 6, I have also pro-

vided a member 8 which completely houses the closure member 6 thereby preventing access to the bolts 7. Suitably connected to the member 6 herein by bolt and nut connection 9 are also members 10 which are circular in shape and which are insertable in apertures 11 in the member 8. Herein it will be noted that the members 10 are further provided with apertures 12 which are adapted to receive a rod 13 extending through openings 14 in the cover member and provided with a head 15 at one end and a locking member, herein in the form of a lock 16, at the other end thereof.

60 The advantages of my improved device 70 will be clearly evident as a result of the description given. After the closure member 6 has been tightly secured in position, the rod 13 is inserted through the apertures 12 and 14 in the members 10 and 8. After the 75 rod is in position, it is locked therein by means of the lock 16. As a result, it will be noted that with the parts thus locked when the machine goes into the mine or into a gaseous part thereof, access to the bolts 7 80 and subsequent removal of the plate 6 by anyone other than the properly authorized person provided with a key to the lock 16 is prevented.

85 While I have in this application specifically described one form which my invention may assume in practice, it will be understood that this form of the same is shown for purposes of illustration and that the invention may be modified and embodied in 90 various other forms without departing from its spirit or the scope of the appended claims.

95 What I claim as new and desire to secure by Letters Patent is:

1. A mining machine presenting a chamber housing electrical connections, an explosion proof cover for said chamber, attaching means for said cover, and means for preventing unauthorized removal of said cover including a shroud for said attaching means and a locking rod interlocking with said cover and shroud.

100 2. A mining machine presenting a chamber housing electrical devices, an explosion 105 proof cover for said chamber, attaching means for said cover including at least one attaching element, and means for preventing unauthorized removal of said cover including a shroud for said attaching element and 110

a locking rod interlocked with said cover and shroud.

3. A mining machine presenting a chamber housing electrical connections, an explosion proof cover therefor, attaching means for said cover, and means for preventing unauthorized removal of said cover including a shroud protecting said attaching means, apertured means carried by said cover, said shroud having apertures to receive said apertured means, and a locking rod passing through said apertured means to obstruct removal of said shroud.

4. A mining machine presenting a chamber housing electrical connections, an explosion proof cover therefor, attaching means for said cover, and means for preventing unauthorized removal of said cover including a shroud protecting said attaching means, apertured means carried by said cover, said shroud having apertures to receive said apertured means and rod receiving apertures, and a locking rod passing through said apertured means and through said rod receiving apertures.

5. A mining machine presenting a chamber housing electrical devices, an explosion proof cover therefor, means for attaching

said cover, and means for preventing unauthorized removal of the latter including a shroud protecting said attaching means and having openings and apertures therein, a plurality of members carried by said cover and projecting into the openings in said shroud, a locking rod interlocking with said members and passing through the apertures in said shroud, and means for locking said rod in position.

6. A mining machine presenting a casing having a chamber housing electrical devices, an explosion proof cover engaging said casing and tightly secured thereto, and means for preventing unauthorized removal of said cover including a supplemental member housing said cover and engaging said casing, said housing member having openings and apertures therein, a plurality of members carried by said cover and projecting into the openings in said housing member, a locking rod interlocking with said last mentioned members and passing through the apertures in said housing member, and means for locking said rod in position.

In testimony whereof I affix my signature.

CHARLES W. WYMAN.
